(57) **CLAIM**

The ornamental design for a vaping device, as shown and described.

DESCRIPTION

FIG. 1 shows an upper perspective view of a vaping device that embodies the ornamental design in an assembled configuration;

FIG. 2 shows a top plan view thereof;

FIG. 3 shows a bottom plan view thereof; FIG. 4 shows a front elevation view thereof; FIG. 5 shows a back elevation view thereof; FIG. 6 shows a right elevation view thereof; FIG. 7 shows a left elevation view thereof; FIG. 8 shows another upper perspective view thereof in a partially exploded configuration for a cap, upper chamber, airflow consolidator, and lower chamber separated from a supportive housing; FIG. 9 shows still another upper perspective view thereof in an exploded configuration for the cap, upper chamber, airflow consolidator, and lower chamber separated from one another; FIG. 10 shows a top plan view of the supportive housing; FIG. 11 shows a bottom plan view of the cap; FIG. 12 shows a front elevation view of the cap, with the back, right, and left elevation views being the same as the front elevation view of FIG. 12; FIG. 13 shows a top plan view of the upper chamber, with the bottom plan view being a mirror image of the top plan view of FIG. 13; FIG. 14 shows a front elevation view of the upper chamber; FIG. 15 shows a back elevation view of the upper chamber; FIG. 16 shows a right elevation view of the upper chamber; FIG. 17 shows a left elevation view of the upper chamber; FIG. 18 shows a top plan view of the airflow consolidator; FIG. 19 shows a bottom plan view of the airflow consolidator; FIG. 20 shows a front elevation view of the airflow consolidator, with the back, right, and left elevation views being the same as the front elevation view of FIG. 20; FIG. 21 shows a top plan view of the lower chamber; FIG. 22 shows a bottom plan view of the lower chamber; and, FIG. 23 shows a front elevation view of the lower chamber, with the back, right, and left elevation views being the same as the front elevation view of FIG. 23.

The broken lines in the drawing depict portions of the vaping device that form no part of the claimed design. The oblique lines in the drawings indicate that those surfaces are transparent.
